COMBINED POCKET LIGHTER AND TAPE MEASURE

David H. Pickering and Edward M. Pickering,
Chicago, Ill.

Application July 25, 1958, Serial No. 51,940

Term of patent 14 years

(Cl. D48—27)

FIG. 1.

FIG. 2.

Figure 1 is a perspective view of a combined pocket lighter and tape measure showing our new design, with the lighter cover in open position and a portion of the tape extended; and

Figure 2 is a reduced perspective view thereof as seen from the opposite side and rear of Fig. 1 with the lighter cover and tape measure in closed position.

We claim:

The ornamental design for a combined pocket lighter and tape measure, substantially as shown.
